UNITED STATES PATENT OFFICE.

PAUL G. OETTEL, OF SPOKANE, WASHINGTON.

MATCH-BLOCK-SAWING MACHINE.

Application filed May 8, 1923. Serial No. 637,482.

To all whom it may concern:

Be it known that I, PAUL G. OETTEL, a citizen of the United States, residing at Spokane, in Spokane County, and State of Washington, have invented certain new and useful improvements in Match-Block-Sawing Machines, of which the following is a specification.

My present invention relates to improvements in match block sawing machines of the gang type wherein the material or planks to be sawed into blocks is conveyed to the gang saws by a combined chain feed and positively driven roller feed. The invention consists in certain novel combinations and arrangements of parts as will hereinafter be pointed out whereby a large capacity of production is attained, a smooth and uniform feed of material is secured, and the proper adjustments of the saws and feed device may be attained with accuracy and facility. Means are also provided in the construction of the machine frame and operating parts whereby a portion of the frame may be moved to give access to the saws for removal, replacement or re-adjustment.

In the accompanying drawings I have illustrated one complete example of the physical embodiment of my invention wherein the parts are combined and arranged according to one mode I have thus far devised for the practical application of the principles of my invention.

Figure 1 is a view in side elevation of the machine, showing the operating means for the combined chain and roller feed mechanism and clutch device therefor.

Figure 2 is a view at the opposite side of the machine illustrating the driving sprocket mechanism.

Figure 3 is a transverse sectional view at line 3—3 of Fig. 4.

Figure 4 is a longitudinal, vertical sectional view of the machine at line 4—4 of Fig. 3.

Figure 5 is a top plan view of a portion of the machine showing relation of the chain and roller feed devices.

Figure 6 is a view with parts in section showing the use of a space plate for alining the feed rollers when they are adjusted for cutting an increased width of the block.

Figure 7 is a perspective view of one of the track-rail adjusting-bars.

Figure 8 is a detail perspective view of one of the notched track rails for support-

ing an endless chain, showing its relation to a transverse brace bar for preventing longitudinal movement of the track rail.

Figure 9 is a sectional detail view of the adjusting device for the rear rollers.

The machine base 1 is of approximately rectangular form and provided with an extension 1^a, and in order to permit ready access to the saws, the upper frame section 2 of the machine is movable vertically, as will be described hereinafter.

The saw arbor 3 is journaled in bearing struts 4 and journal boxes 5 as usual and extends transversely of the fixed lower portion or base of the machine. The saws 6 are arranged on the arbor 3 in parallel spaced formation and separated by the spacing collars 7 which are provided in sets of different widths for use in cutting different sizes of match blocks from the planks, the latter being fed to the gang saws in a direction perpendicular to the grain of the wood in the planks. Usual devices including a lock nut 8 on the arbor, are employed, and the saws, through the arbor are positively driven from the pulley 9 on the arbor. The main pulley 9 is driven by belt in usual manner from a suitable source of power, not shown.

The planks, to be cut into blocks, are fed to the gang of saws with uniformity and accuracy by a combined endless chain and roller feed, the former comprising a suitable number of chains for supporting the plank which extends transversely of the chains, and the latter comprising a series of positively driven rollers and guide rollers adapted to bear down upon the tops of the planks as they are fed to the saws.

The endless chains are indicated by the numeral 10 and their straight working flights, which support the planks are indicated by the numeral 11, said working flights extending from front to rear of the machine and of course arranged in parallelism. The feed chains are supported in the upper frame section 2 of the machine between a series of grooved wheels 12 at the front of the machine and a series of driving sprocket wheels 13 at the rear of the machine, these two sets of wheels being carried by the respective shafts 14 and 15, journaled in suitable bearings in the movable section or frame 2 of the machine.

Power for operating the endless chain feed is transmitted from the small pulley

16 on the saw arbor, through a belt 17 to the larger pulley 18 on a worm shaft 19 which extends transversely of the chains and is journaled in bearings in the base of 5 the machine. A worm gearing of usual type is provided within the casing 20 for transmitting power from the worm shaft 19 to an angularly disposed clutch shaft 21 which is journaled in bearings 22 and im- 10 parts rotary motion to the vertical, gear shaft 23 through the bevel gears 24 and 25 as best seen in Fig. 1. The vertical shaft 23 is located at one of the rear corners of the machine and is journaled in a bearing 15 26 rigid with the base 1 of the machine and also journaled in a bearing 27 rigid with the movable frame 2 of the machine and slidable on the shaft when the section 2 is elevated or lowered. The shaft 15 of the 20 chain feed mechanism is driven from the shaft 23 by pinion 28 on the latter and gear 29 on the former.

The chains may be of the roller type and each chain is supported throughout the 25 length of its working flight 11 by a track-rail 30, the rails being arranged parallel with the chain flights and beneath them to form a stable support. To prevent longitudinal movement of the track rails a rigid 30 brace bar 31 is provided, which is fixed and supported in the base 1 of the machine beneath the rails and extends transversely of the series of rails. Each track rail is notched as at 32 to fit over the top edge of 35 the brace bar and in this manner the rails are anchored against longitudinal movement. At its respective ends each track rail is provided with a curved plate as 33 which is complementary to the supporting 40 rollers 12 and 13 of the feed chains, and the series of rails is supported near the front and rear ends of the machine by means of supporting bars 34 and 35. These bars are cylindrical in cross section and journaled in 45 the side walls of the upper frame section 2, and the ends of the bars are squared as at 34' and 35' for the reception of a wrench or other hand tool. At regular intervals throughout the length of each bar annular 50 grooves are provided corresponding to the spaced distance of the track rails, and the surfaces 36 of these grooves which are flat, form eccentric, rectangular, webs. Thus it will be apparent that by means of a wrench 55 the supporting bars may be turned in their bearings to present an upper flat face 36 upon which the track rail rests and the height of the track rail above the longitudinal center of the supporting bar is determined by selection of one of the flat faces 60 36 of the supporting bar. The two bars are of course turned in unison and the flat faces selected to support the track rails in horizontal position.

65 The vertical adjustment of the track rails

is accurately obtained and maintained by means of a pair of eccentric adjusting bars 37 and 38 complementary to the supporting bars 34 and 35 and journaled also in the side walls of the frame 2. Each of these 70 bars has a complementary series of eccentric disks 39, spaced apart to register with the spaced track rails and engage against the lower edges of the rails. A wrench is applied at the squared ends of these adjusting 75 bars and the bars are turned in their bearings to secure proper adjustment of the rails through the eccentric disks 39, to level or adjust the track rails. Four different 80 adjustments are provided for by the flattened portions of the bars 35 and 36. As will be seen in Fig. 3 through the action of these eccentric disks 39, the throw of which is greater than that of bars 34 and 35, the 85 rails are first elevated by the action of the disks, and then the desired flat faces of the bars 34 and 35 are turned to top position. Then the adjusting bars 38 and 39 are turned to lower the rails on these top or upper faces of the bars 35 and 36.

In connection with the chain feed I employ a series of positively driven feed rollers, supported above the chains in the frame 2 of the machine. Three parallel, transversely disposed shafts 40, 41, 42, are employed for the roller feed and journaled in vertically adjustable bearing blocks 43.

The bearing blocks are adjustably supported in the side walls of the frame 2 which are slotted for the purpose, and bolts or screw bars 43' may be utilized for the purpose of adjusting the shafts with relation to the position of the feed chains. Each shaft carries a series of feed rollers 44, the rollers of the shafts being arranged in staggered relation, and keyed on their respective shafts so that they may be adjusted longitudinally of the shafts to correspond with the spaced relation of the feed chains. As shown the staggered rollers are 100 of a diameter so that they overlap, thus securing the advantage of comparatively large diameters, and close arrangement of the shafts, to insure proper grip of the planks between the rollers and chains of the feeding mechanism.

For maintaining the proper adjustment and distance between the rollers of the several sets I employ a set of spacing plates 45 of uniform thickness and interposed between adjoining rollers on each shaft. At their lower edges these plates are notched, as at 46 to fit over the shafts 40, 41, 42, and at their ends they are provided with notches 47 to fit over the anchoring bars 48 and 49, the former located at the rear of the machine and the latter in front of the feed rollers, and both fixed in the side walls of the frame section 2. A connecting rod 50 may be passed through registering holes in the sev- 115 120 125 130

eral space plates and supported in the side walls of the frame 2 to maintain the plates in rigid relation. The plates are made up in sets of varying thickness, but the plates 5 of each set are of similar thickness to provide uniformity in spacing the rollers.

The feed rollers are positively driven from the vertical shaft 23, as seen in Fig. 1 through the gear coupling 51 and 52, the latter on the sprocket drive shaft 53 journaled in the walls of the frame 2 at the rear or delivery end of the machine and extending transversely thereof. In Fig. 2 will be seen the main sprocket wheel 54 on this 10 shaft from which the main sprocket chain 55 extends over and drives the sprocket wheel 56 on shaft 41. Idle wheels 58 and 59 are employed to guide the main sprocket chain as seen in Fig. 2. An auxiliary 15 sprocket wheel 60 is carried at the end of the shaft 49 (Figs. 2 and 4) and the chain 61 from this wheel passes around and drives shaft 42 through the wheel 62 on said shaft. At the opposite end of shaft 42 (see Fig. 1) 20 a wheel 63 is carried, and through the chain 64 passing around the wheel 65 on shaft 40 the latter is driven.

The feed rollers, as seen in Fig. 3 are arranged to present the planks to the saws for cutting the planks into blocks, and in addition to these positively driven feed rollers I employ pressure rollers for engaging the plank as it is being sawed to prevent kick-back of the material due to action of 25 the saws. Two sets of these rollers, 66 and 67, are used to retain the plank on the feed chains until it has been passed from the saws, as seen in Fig. 3, and they are arranged parallel with the sets of feed rollers 30 between them and the rear end of the machine. These rollers are gravity actuated and are suspended in staggered relation, one roller over each feed chain or in position to co-act therewith. A number of the 35 rollers 66 are arranged in series, each supported from an independent arched-arm 68 disposed above the feed rollers and provided with a hub 69 journaled on the anchoring bar 49 previously referred to. Each 40 arm has an extension lug 70 projected toward the front of the machine from its hub 69 and disposed in horizontal position, and excessive downward movement of the series 45 of rollers is limited or prevented by the utilization of a single retaining bar 71. The retaining bar is disposed transversely of the feed chains and is supported in end brackets 50 72 (see Fig. 9) which are fixed to the side walls of the frame 2. A vertically arranged 55 screw bar 73 is supported in each bracket and passes through a threaded opening in the end of the retaining bar. By turning the screw bar or bolt 73 it will be apparent 60 that the retaining bar may be raised or lowered and by means of the lock nut 74 on the

bolt the latter may be secured in adjusted position. A set bolt 75 in the bracket, above the end of the retaining bar may be used to limit movement of the retaining bar.

The rollers 67 are also arranged in series 70 and each roller is supported from a suspending arm 76 which extends toward the rear of the machine. Each arm has a hub 77 journaled on anchoring bar 48 and a rearwardly extending lug 78 is projected horizontally from the hub as seen in Figs. 3 and 5. The alined lugs 78 are held by gravity against the under edge of a retaining bar 79 which performs a function similar to the retaining bar 71. The retaining bar is supported from a cross bar 80, which is provided with attaching bolts 81 passing through slots in the retaining bar, and adjusting bolts 82 supported in brackets 83 of the cross bar are used to adjust the retaining bar relatively to the cross bar, the two bars being then clamped together by the bolts 81. The two sets of pressure rollers 85 may be provided with oil cups as 84 for lubrication purposes.

The movement of the two sets of suspending arms and their rollers is thus limited and adjusted by the position of the retaining bars, and the rollers are actuated by gravity to bear upon the sawed planks as they leave 95 the saws to prevent kick back by the saws, and the cut blocks are delivered by the chains at the rear ends thereof.

The upper frame of the machine may be elevated, carrying with it the chain and 100 roller feed mechanism and supports, to gain access to the saws for replacement and readjustment. As seen in Fig. 1 a supporting guide plate 85 is provided at each of the four corners of the machine and bolted 105 to the frame section 2, with its lower end slotted as at 86 and projecting down alongside the wall of the base 1. Bolts 87 are fixed to the base, pass through the slots of the plates, and clamp nuts 87' are used to 110 rigidly hold the plates to the base member of the machine.

To elevate the upper section or frame 2 these bolts and nuts are loosened and the plates guide the movement of the movable 115 frame 2. At each of the four corners of the machine is a screw bar, as 88, one of which may be an operating bar. These bars are vertically disposed and each is supported from the base to revolve in a stationary nut 120 89. At 90 on the movable frame a fixed bearing is provided for the screw bar as seen in Fig. 3. These screw bars are actuated, manually, by a wrench or other tool applied to the squared end of a stud shaft 125 91 and its pinion 92 which revolves a cross shaft 93 journaled in the bracket 94. This shaft extends across the front of the machine and is provided at its ends with a bevel gear 93 to engage with and revolve 130

a complementary gear 95 on the screw bars, or at least on two of them. At each side of the machine frame 2 and within the frame is journaled a connecting shaft as 96 extending parallel with the feed chains, each of which shafts connects a pair of screw bars by a gear coupling as 97, 98. As thus arranged, by manually turning the stud shaft 91, the four screw bars may be simultaneously and synchronously revolved in their stationary nuts to elevate or lower the movable frame with relation to the machine base. When the frame is elevated access may be had to the saws and the entire assembly of the gang saws including the arbor, collars and bearing strut may be detached and removed, and replaced. The saws, the feed chains, feed rollers and pressure rollers are all adjusted and spaced with proper relation one to another for uniformity in operation.

A clutch device is indicated at 99 (Fig. 1) on the clutch shaft 21 to control the feed mechanism.

By proper adjustment the saws may be spaced, together with the feed mechanism, to accommodate the machine for various cuts of blocks, and by the described means the feed devices may readily be adjusted to accommodate different thicknesses of planks.

Having thus fully described my invention what I claim as new and desire to secure by Letters Patent is:

1. The combination in a sawing machine with a series of spaced parallel feed chains and operating mechanism therefor, of a complementary series of supporting track-rails, means for elevating the rails and rotatable bars having selective faces for supporting said rails in elevated position.

2. The combination in a sawing machine with a series of spaced parallel feed chains

and operating mechanism therefor, of a complementary series of track-rails, means for retaining said rails against longitudinal movement, a pair of supporting bars for said rails each having annular grooves complementary to the rails, and flat faces in said grooves variously spaced from the longitudinal center of the bars.

3. The combination with a series of track rails of a pair of complementary supporting bars suspended transversely beneath said rails, each bar having spaced annular grooves complementary to the rails and angular webs forming the inner walls of said grooves with faces at various distances from the center of the bar.

4. The combination with a series of track rails of a pair of transversely disposed supporting bars forming bearings for said bars, each bar having spaced annular grooves and rectangular webs forming the inner walls of said grooves comprising flat faces disposed at various distances from the longitudinal center of the bar.

5. The combination with a series of track rails of a pair of transversely grooved bars having angularly disposed supporting faces within said grooves and rotatable to adjusted position, and a pair of complementary adjusting bars having eccentric disks thereon for engagement with said rails.

6. The combination with a series of spaced feed chains, of vertically adjustable track rails beneath said chains, a brace bar disposed transversely of said rails, and notches in said rails for co-action with said brace bar to prevent longitudinal movement of the rails and means for supporting said rails in adjusted position.

In testimony whereof I affix my signature.

PAUL G. OETTEL
